UNITED STATES PATENT OFFICE

2,547,061

MULTIPLE GAP VELOCITY MODULATION TUBE

Emile Tournon, René Zwebada, and Anne-Marie Gratzmuller, Paris, France, assignors to International Standard Electric Corporation, New York, N. Y., a corporation of Delaware

Application September 8, 1947, Serial No. 772,623
In France December 17, 1945

Section 1, Public Law 690, August 8, 1946
Patent expires December 17, 1965

6 Claims. (Cl. 315—6)

1

The present invention relates to wide band velocity modulation tubes that make use of highly damped multiple cavity resonators.

The necessity of having damped cavity resonators for the production of wide bands requires a high input power, and implies a low output power. This lowers the gain in an amplifier tube and lessens the performance for oscillating tubes.

One of the objects of the present invention is to provide velocity modulation tubes that permit the use of wide bands having a high gain when they are employed as amplifiers, and a high performance when they are used as oscillators.

Since the amplification factor and the band width of an amplifier are two factors affected by the same parameters, the present invention relates to increase of the gain of an amplifier having constant band width, or increase of the band width of an amplifier of constant gain.

According to one feature of the present invention, use is made of multiple gaps exclusively for the velocity modulation of the electrons in the beam, or for the catching of high frequency energy from the beam, or for both. The multiple gaps are associated either with separate resonant volumes in alignment along the electron beam path, or with a single resonator. The electrons are given a high velocity in the modulation and the catching spaces.

Other objects or features will be apparent to those skilled in the art upon reading the following description of one example of an embodiment of the invention given with reference to the appended drawings, in which:

Fig. 1 shows a velocity modulation tube incorporating features of the present invention;

Fig. 2 shows a variant of a cavity resonator with multiple gaps for use in the tube of Fig. 1;

Fig. 2A shows a velocity modulation tube incorporating the features illustrated in Fig. 2; and

Fig. 3 shows a tube with a beam of sheet shape, that employs features of the present invention.

As shown in Fig. 1, the electron gun consists of an indirectly heated cathode K and a Wehnelt cylinder W at negative potential from source 1, and it furnishes a cylindrical electron beam.

An exciting cavity resonator R₁ is provided with three modulation or bunching spaces a, b, c, and is brought by source 2 to a positive potential that is high relatively to the cathode. The field produced by this electrode imparts a high average velocity to the electrons as a result of the fact that it is brought to a high positive potential with respect to the cathode.

2

In the embodiment shown by way of example, a low voltage electrode E₁ connected to source 3 produces a field that maintains the cylindrical shape of the beam, while braking it down to a low velocity. This electrode forms the closure of the drift space.

An output cavity resonator R₂, provided with three catching spaces in which the electrons give up their high frequency energy, is brought to a high positive potential by source 4 relatively to that of the cathode and therefore imparts a high average velocity to the electrons.

A target electrode E₂ placed at low voltage by source 5 effects the recovery of the electrons in a manner known to the art. It is surrounded by a cylinder placed at slightly higher potential by source 6. The shape is designed so as to prevent secondary emission, and it also forms the closure of the end of the beam path.

20 The tube is enclosed by an envelope 7 through which the connections to the various electrodes are sealed. An input transmission line 8 is coupled to resonator R₁ by a loop 9 and an output line 10 is coupled to resonator R₂ by a loop 11. The two transmission lines are sealed through the envelope of the tube and furnish external means for connecting to the cavity resonators.

Fig. 2 shows a variant of a multiple gap cavity resonator R₃. According to this variant, the electron beam successively passes through the channels provided in metallic masses of parallelepiped shape. These masses m are secured alternately to opposite sides of a guide of rectangular section.

35 A device of this kind may also be used in an oscillator or an amplifier that employs an electron beam of convergent sheet shape. The cavity resonator is then given such a shape that supplementary electrodes as shown in Fig. 3 cause the beam to converge in the successive modulation or bunching spaces, and similarly in the catching spaces.

In Fig. 2A a velocity modulation tube is shown 45 similar to that illustrated in Fig. 1 with an input cavity resonator R_{3'} and an output cavity resonator R_{3''} constructed in accordance with the embodiment shown in Fig. 2. The elements illustrated in Fig. 2A which are identical to the elements of Fig. 1 have been given the same reference characters. The resonators R_{3'} and R_{3''} have been shown in section across the shortest dimension of the resonators, showing the metallic masses m in longitudinal section.

50 55 In Fig. 3, the multiple gaps in resonator R₁ are indicated by a, b, c, and in resonator R₂ by d, e, f

The transit channels T_1 and T_2 in resonator R_1 , and T_3 and T_4 in resonator R_2 , are shown in the form of two truncated conic portions disposed as in the drawing, although use may be made of electrodes of very different shapes according to the various uses to which the invention is applied, the shape of the electrodes being only dependent on the condition that they must effect the convergence of the electron beam at the level of the gaps a , b , c and d , e , f .

In order to facilitate the obtaining of this convergence, it is possible to provide electrodes 12, 13, 14, 15, 16, 17, 18, 19, that are dimensioned and disposed so as to improve the desired convergence effect.

Electrode E_1 has a shape and a potential suitable for effecting a desired spreading of the electron beam.

The mode of operation of devices of this kind is as follows:

During the first modulation, when cylindrical cavity resonator R_1 comes into resonance, two successive gaps such as a and b are subjected at a given moment to two unidirectional voltages, and the transit time of the electrons from one gap to the next one is a multiple of a period; this results in the effects of the high frequency field being additive.

On the other hand, in the variant of the guide of rectangular section shown in Fig. 2, two alternating voltages of opposite directions exist at a given moment in two successive gaps, and one same mass m is equipotential, since it is integral with one same face of the guide, and the transit time of the electrons from one gap to the next is then an odd multiple of a half period.

If R is the resistance at the terminals of a modulation space, U the high frequency voltage at the terminals of this space, and n_1 the number of gaps, the power furnished to the beam is

$$\frac{n_1 U^2}{R}$$

For obtaining the same depth of modulation of the same beam at the terminals of a single gap, it would be necessary to furnish the voltage $n_1 U$ to the terminals of resistance R , i. e. a power

$$\frac{n_1^2 U^2}{R}$$

which is n_1 times greater than when multiple gaps are used.

At the output end, if r is the resistance at the terminals of a gap, i the value of the fundamental component of the alternating current, and n_2 the number of gaps, the power given up by the beam to the cavity is $n_2 r i^2$ times greater than if the beam was braked only once by the high frequency field. The gain, when used as an amplifier, is accordingly multiplied by $n_1 n_2$.

This device may also be used in a frequency multiplier tube.

High voltages have been employed, because the number of gaps that it is possible to use is limited by the transit time of the electrons from the first gap to the last one, and accordingly by the speed of travel, which is itself dependent on the voltage.

If, indeed, upon excitation, the distance between the end gaps is too great, the bunching effected by the modulation in the first gap begins to have effect, and the alternating component of the thus obtained current acts on the subsequent gaps. This results in a variation of the

impedance at the terminals of the last gap, but this is partially corrected by the shape of the gap and of the transit channel in the cavity.

In the catching space, the number of gaps employed is limited by the fact that they must be located at points along the electron beam path where transfer of ultra high frequency energy from the beam to the field in the resonator will be a maximum. The output voltage U_2 , of a resonator excited by an electron stream velocity modulated by an input resonator and bunched in a drift space varies with the distance along the path of the stream at which the output resonator is excited by the stream. This variation is in accordance with the Bessel function of the fundamental component of the modulated current.

$$J_1\left(\frac{\omega s}{2v_0} \frac{U_1}{U_0}\right)$$

In this expression

ω is the pulsation of the fundamental component, s is the distance from the modulation space or gap to the catching space at which the output voltage U_2 is excited in the output resonator, v_0 is the mean velocity of the electron in the drift space of distance s , U_1 is the modulation voltage, U_0 is the potential of the electrode E_1 about the drift space.

The gaps are grouped in such a way as to correspond to points situated in the vicinity of the maximum of the Bessel function.

While we have described above the principles of our invention in connection with specific apparatus, it is to be clearly understood that this description is made only by way of example and not 40 as a limitation on the scope of our invention.

We claim:

1. A velocity modulation electron discharge device comprising a source of an electron beam and a collector electrode defining a beam path, a cavity resonator disposed about said beam path adjacent said source for velocity modulating electrons in the beam, said modulating resonator including a wave guide of rectangular section and masses of parallelepiped shape located along the beam path inside said guide and supported alternately on opposite sides of said guide, said masses being provided with apertures for passage of the beam therethrough, said masses defining therebetween a plurality of gaps along the beam path for permitting an electromagnetic field developed in said resonator to velocity modulate the electrons in the beam successively at each said gap, and a cavity resonator disposed about said beam path adjacent said collector electrode for extracting ultra high frequency energy from the velocity-modulated electron beam, said extracting resonator being provided with a gap for permitting the electron beam to supply energy to an electromagnetic field developed in said extracting resonator.

2. An electron discharge device according to claim 1 in which said energy extracting cavity resonator comprises a wave guide of rectangular section and masses of parallelepiped shape located along the beam path inside said guide and supported alternately on opposite sides of said guide, said masses being provided with apertures for passage of the electron beam therethrough, said masses defining therebetween a plurality of gaps along said beam path for permitting an electromagnetic field developed in said resonator to ex-

tract energy from the electrons in the beam successively at each said gap.

3. A device as set forth in claim 1 in which the said masses are equal in length in the direction of the beam path whereby the transit time of the electrons from one gap to the next is adjusted to be an odd multiple of a half period of the operating frequency.

4. A velocity modulation electron discharge device comprising a source of an electron beam and a collector electrode defining a beam path, a cavity resonator disposed about said beam path adjacent said source for velocity modulating electrons in the beam, and a cavity resonator disposed about said beam path adjacent said collector electrode for extracting ultra high frequency energy from the velocity-modulated electron beam, said extracting resonator including a wave guide of rectangular section and masses of parallelepiped shape located along the beam path inside said guide and supported alternately on opposite sides of said guide, said masses being provided with apertures for passage of the beam therethrough, said masses defining a plurality of gaps along the beam path for permitting the velocity-modulated electron beam to supply energy to an electromagnetic field developed in said resonator successively at each said gap.

5. A velocity modulation electron discharge device comprising an electron beam source and a collector electrode defining a beam path, a cavity resonator disposed about said beam path adjacent

said beam source for velocity modulating electrons in said beam, and a cavity resonator disposed about said beam path adjacent said collector electrode for extracting energy from the velocity modulated electron beam, each of said cavity resonators having means for communication with said electron path, one of said resonators including a wave-guide section with masses spaced apart along the beam path inside said guide and supported alternately on opposite sides of said guide, said masses having apertures for passage of the beam therethrough.

6. An electron discharge device according to claim 5, wherein said waveguide section is rectangular in cross-section and said masses are of parallelepiped shape.
